TEXTURED PLASTIC COATED FABRIC

Herbert Williams Thurlow, Babylon, N.Y., assignor to
Riegel Textile Corporation, a corporation of Delaware

Filed Nov. 24, 1959, Ser. No. 58,458

Term of patent 14 years

(Cl. D87—3)

The single figure is a plan view of a textured plastic coated fabric incorporating my new design.

I claim:

The ornamental design for textured plastic coated fabric, as shown.
